UNITED STATES PATENT OFFICE.

MAX H. ROSENTHAL, OF LOS ANGELES, CALIFORNIA, ASSIGNEE TO TECHNICAL GLASS COMPANY, INC., OF LOS ANGELES, CALIFORNIA.

DESIGN FOR A DRAWER KNOB.

Application filed August 29, 1924. Serial No. 10,583. Term of patent 7 years.

To all whom it may concern:

Be it known that I, MAX H. ROSENTHAL, a citizen of the United States, residing at Los Angeles, in the county of Los Angeles and State of California, have invented a new and original Design for Drawer Knobs, of which the following is a specification, reference being had to the accompanying drawing, forming part thereof.

Figures 1 and 2 are top plan and side elevational views, respectively, of a drawer knob, showing my new design.

I claim:

The ornamental design for a drawer knob, as shown.

MAX H. ROSENTHAL.
